United States Patent Office

Des. 213,59
Patented Mar. 18, 19

213,591

COMBO ORGAN OR SIMILAR ARTICLE

John G. Gagne, Fort Erie, Ontario, Canada, assignor to
The Wurlitzer Company, Chicago, Ill., a corporation
of Ohio

Filed Oct. 9, 1967, Ser. No. 8,915

Term of patent 14 years

U.S. Cl. D56—2
Int. Cl. D17—01

Fig. 1.

Fig. 2.

Fig. 3.

Fig. 4.

FIG. 1 is a front perspective view of a combo organ or similar article showing my new design;

FIG. 2 is a rear perspective view thereof;

FIG. 3 is a horizontal cross sectional view, partly in top plan, taken substantially along the line 3—3 on FIG. 1; and

FIG. 4 is a right side elevational view, the left side being substantially a mirror image thereof.

The dominant features of my design reside in the portions shown in full lines.

I claim:

The ornamental design for a combo organ or similar article, as shown.
